UNITED STATES PATENT OFFICE.

EDWARD R. HOLLIS, OF LOUISVILLE, KENTUCKY.

PLATE-GLASS-BUFFING MACHINE.

1,186,399.

Specification of Letters Patent.

Patented June 6, 1916.

Application filed December 8, 1915. Serial No. 65,846.

To all whom it may concern:

Be it known that I, EDWARD R. HOLLIS, a citizen of the United States, residing at Louisville, in the county of Jefferson and State of Kentucky, have invented new and useful Improvements in Plate-Glass-Buffing Machines, of which the following is a specification.

My invention relates to a machine for buffing or polishing the bevel edge of plate glass, and one of its objects is to provide a machine whereby the glass may be polished in such a manner as to lessen or eliminate breakage through pressure methods, whether by hand or machinery; and also to provide a machine which produces a highly satisfactory finish without the necessity of preliminarily polishing the glass on a pumice wheel, as is generally required.

20 A further object of the invention is to provide a machine which is adjustable to suit the bevel surface which is to be polished, which when adjusted will operate with the exact degree of pressure required, and no more, which may be adjusted to vary its pressure to any extent required; and which is adapted to operate rapidly and economically.

25 A still further object of the invention is to provide a buffing machine of the character described which is simple of construction, inexpensive of production and maintenance, which may be readily and conveniently thrown into and out of operation, and in which the buffing wheel may be removed and applied with facility, so that a different wheel may be employed and various kinds of wheels interchangeably used as may be desired or required.

30 The invention consists of the features of construction, combination and arrangement of parts herein fully described and claimed, reference being had to the accompanying drawings in which:

35 Figure 1 is a view in side elevation of an automatic buffing machine embodying my invention. Fig. 2 is a top plan view of the machine proper. Fig. 3 is a detail transverse section on the line 3—3 of Fig. 2. Fig. 4 is a view in elevation, on an enlarged scale, of the lever mechanism, looking from a point at right angles to that shown in Fig. 1.

40 Referring to the drawings, the numeral 1 designates the cast iron frame or wheel carrier bracket of the device which comprises a bar-like body of suitable dimensions which

is loosely pivoted at its rear end upon a drive shaft 2, which shaft may in practice be driven from any suitable source of power and is journaled in suitable bearing standards 3.

45 The shaft 2 carries a drive pulley 4 which is connected by a belt 5 with a pulley 6. The pulley 6 is mounted upon one end of a buffing shaft or mandrel 7 journaled in suitable bearings 8 upon the arms or divisions 9 of the slotted forward end of the frame 1, in the slot 10 of which is arranged a buffing wheel 11 suitably fixed to the shaft 7. As shown in the present instance, the wheel 11 50 is provided with a polishing surface 12, of felt or other suitable material, but may have a facing of any suitable kind of buffing material, said wheel projecting through the slot 10 and being fixed in any preferred manner 55 to the shaft 7 to rotate therewith, whereby said buffing wheel is driven.

60 The frame 1 is adapted to tilt vertically upon the shaft 2 as an axis, to bring the polishing surface of the wheel 11 into or out of engagement with the beveled surface 13 of the glass plate 14 which is to be polished. This plate 14 rests upon a table 15 of the character commonly employed, said table being mounted on wheels 16 for movement at 65 right angles to the plane of rotation of the buffing wheel, whereby the glass plate may be adjusted to bring the different portions of the beveled edge 13 in position to be buffed. The movement of the table can be 70 limited in extent to any amount desired and by any suitable means.

65 The weight of the frame and wheel is utilized to hold the buffing surface of the wheel with the desired pressure against the surface of the work. This pressure may be regulated and the extent of downward movement of the frame regulated by means of an adjusting and supporting screw 17 and the lower end of which is arranged to bear 75 against a supporting pedestal 18 and the upper end of which is provided with a head or other surface 19 for engagement with a wrench or other tool whereby the screw may be adjusted. As shown, the screw is fitted 80 in and extends through a threaded opening 20 in the frame and is adapted to be held in adjusted position by a check nut 21. It will 85 thus be seen that, after the machine has been once set, the periphery of the buffing wheel 90 will be disposed to bear with the exact amount of pressure required against the 95

beveled surface to be polished while polishing the different portions of said surface or of another surface of the same bevel and the necessity of readjusting the machine is avoided.

It will be evident that through the medium of the screw 17, which regulates the position of the periphery of the wheel 11 with respect to the edge of the glass which is to be polished, any desired pressure up to the full weight of the apparatus may be obtained on the surface of the work, so that it may be buffed or polished in an accurate manner and to an exact degree. Also it will be seen that since the pressure may be regulated to the utmost nicety, and that since undesirable and unnecessary violence of roughness of contact between the glass and parts of the apparatus will be entirely eliminated, liability of injury to or breakage of the glass will be reduced to a minimum.

It will be obvious from the foregoing description that the construction is such that the frame 1 and wheel 11 may be moved about the shaft 2 without altering the relative position of the pulleys or other working parts, thus allowing the device to be lifted from the work without disturbing the adjustment of any of its parts. Furthermore, the wheel 11 may be quickly removed from the shaft 7 upon disengaging the latter, and another wheel of like character or of a different kind may be quickly applied in lieu thereof, thus allowing a new wheel to be substituted for an old one or interchangeable buffing or polishing wheels of different kinds to be readily and conveniently employed.

The means for raising and lowering the device into and out of engagement with the work comprises a rod 22 which is pivotally connected at its lower end with the front end of the bracket or frame 1, as indicated at 23, and is slidably mounted at its upper end in a supporting hanger 24. Also mounted on this hanger is a pivoted hand lever 25 connected by links 26 with pairs of toggle levers 27 and 28, the levers 27 being pivotally connected with the hanger 24 and the levers 28 pivotally connected with an adjustable sleeve 29 on the rod 22 whereby said rod may be readily and conveniently raised and lowered to raise and lower the carrier bracket or frame buffing wheel out of and

into engagement with the surface of the work, a raising, lowering mechanism of a simple but powerful character being thus provided whereby comparatively heavy buffing devices may be raised in a ready and convenient manner.

In addition to the above stated advantages, it is evident that the apparatus is simple and inexpensive of construction, capable of being operated at a minimum cost, and adapted to perform its work in a rapid and efficient manner.

I claim:

1. A buffing machine comprising a drive shaft, a vertically swinging carrier bracket journaled at one end to swing upon said shaft as an axis, a buffing wheel journaled upon the free end of said carrier bracket, a driving connection between the buffing wheel and the drive shaft, said connection being movable with the carrier member, a raising and lowering element connected with the free end of the carrier member, and an overhead operating device for actuating said raising and lowering element.

2. A buffing machine comprising a carrier member, pivotally mounted at one end to swing in a vertical plane, a buffing wheel journaled upon the free end of said carrier member, means for driving said buffing wheel, means for adjustably limiting the downward movement thereof, a vertically sliding raising and lowering rod connected with the free end of the carrier member, and an overhead actuating means for raising and lowering said rod.

3. A buffing device including a pivotally mounted gravity controlled supporting bracket, a buffing wheel journaled on said bracket, means for driving said buffing wheel, means for regulating the downward movement of the bracket and buffing wheel and pressure of the latter on the work, a slideable rod pivotally connected with the bracket, and a toggle lever mechanism connected with said rod whereby a supporting bracket may be raised and lowered.

In testimony whereof I affix my signature in presence of two witnesses.

EDWARD R. HOLLIS.
